UNITED STATES PATENT OFFICE.

WILLIAM S. HAMM, OF HUBBARD WOODS, AND THOMAS A. LEGGE, ALFRED H. NEWPHER, AND CARL J. EKBERG, OF CHICAGO, ILLINOIS, ASSIGNORS TO THE ADAMS & WESTLAKE COMPANY, A CORPORATION OF ILLINOIS.

SASH-BALANCE.

1,178,583.

Specification of Letters Patent. Patented Apr. 11, 1916.

Application filed July 15, 1914. Serial No. 851,099.

To all whom it may concern:

Be it known that we, WILLIAM S. HAMM, of Hubbard Woods, county of Cook, and State of Illinois, and THOMAS A. LEGGE, ALFRED H. NEWPHER, and CARL J. EKBERG, all of Chicago, county of Cook, and State of Illinois, and all citizens of the United States, have invented, jointly, certain Improvements 10 a specification, and which are illustrated in the accompanying drawings, forming a part thereof.

The invention relates to windows having one or more sliding sashes; and its object is 15 to provide improved means for balancing the sash and for retaining it within the casting.

An embodiment of the invention is herein described, and shown in the accompanying 20 drawings in which—

Figure 1 is a detail elevation of a window partly in section, and some parts being broken away; Fig. 2 is a detail in perspective of a portion of the window sash and casting, and of the balancing mechanism; Fig. 25 3 is a detail, partly in section, of the spring balance; Fig. 4 is a sectional detail on the line 4—4 of Fig. 1; Fig. 5 is a sectional view on the line 5—5 of Fig. 1; Fig. 6 is a sectional detail on the line 6—6 of Fig. 3; Fig. 30 7 is a vertical sectional detail through the window casing; Fig. 8 is a detail of the edge of the sash and the end of the balancing spring mechanism; Fig. 9 is a detail longitudinal section of the end portion of the 35 balancing device; and Fig. 10 is a detail of the sectional intermediate stop, the portions being separated.

While the invention is applicable to any 40 window provided with one or more sliding sashes, it is shown as applied to a double sash car window.

The window casing is shown as comprising a bottom rail 10, and side members 11, 45 12. A pair of sashes 13, 14, are slidably mounted between suitable stops. In the present instance there is shown a spring-advanced stile 15, one associated with each of the upright members of the window casing 50 and engaging the side edges of the sashes. Outer guide stops are shown at 16, 17, the stile plate 15 being slidably mounted therebetween and held in advanced position by springs, as 17^a. In car construction

where the window opening is substantially 55 of the height of a single sash, the upper portion of the stile plate is preferably provided with instanding flanges 18, 19, which form continuations upward of the stops 16, 17.

An intermediate stop is secured to the 60 plate 15 and engages the adjacent faces of the two sashes. The upper portion of the intermediate stop is provided with an instanding flange 21, upon the side faces of which are formed gear teeth 22, thereby providing 65 a rack which extends upwardly through the entire range of movement of the sash and its appurtenances. The intermediate stop is formed of a plurality of sections. The upper section 20 is intended to be permanently 70 attached to the stile plate by any suitable means. The lower section is removably held in place as and for the purpose herein-after stated.

The gear rack 22 extends down onto the 75 upper portion of the lower section of the intermediate stop to a point below the spring-controlling pinion 30.

The sash balance comprises a helical spring carried by the sash and having one 80 of its ends anchored thereto, its opposite end being attached to a revoluble member provided with a pinion which is in engagement with the rack 22. Such a spring is represented at 23, and as being housed 85 within a cylindrical casing 24, and as being secured thereto at one end, as shown at 25. The casing 24 is mounted upon the upper rail 26 of the sash, with which it cooperates, and is provided at its inner end 90 with a gudgeon 27, journaled within a bracket 28 fixed to the sash rail. The outer end of the casing has attached thereto a shaft member 28^a, sleeved upon a shaft 29 and bearing a pinion 30 in mesh at all times 95 with the rack 22.

The shaft 29 projects beyond the pinion 30, its outer end 31 being fixedly held within a bracket 32 secured to and extending above the sash. The inner end 33 of 100 the shaft 29 fits within a block 34 fixed within the inner end of the casing 24. The outer end of the spring 23 is attached to the shaft 29, as shown at 35. By this arrangement as the sash is moved the 105 pinion 30 is rotated and with it the casing 24, thereby coiling or uncoiling the spring 23. The parts are so assembled that when

the sash is in its lowest position the spring is tightly coiled, and hence under tension, and tends to raise the sash, though preferably of insufficient strength to lift it unaided. As the sash is drawn down from its raised position the spring is rewound.

In order that the spring may be placed under tension before the sash is inserted within the casing, a lock is provided for preventing the relative rotation of the shaft 29 and the casing 24. In the construction as shown the lock comprises a circular block 36 pinned to the shaft 29, and having ratchet teeth 37 on its disk face, and a stud 38, carried by a sleeve 39 slidably mounted upon but rotating with the casing 24 and the member 28^a, extends inwardly through a longitudinal slot 40 in the casing, and, when in one position, engages the ratchet teeth 37, preventing the movement of the ratchet relatively to the casing to unwind the spring.

A helical spring 41, coiled around the casing 24, reacts between the inner end of the sleeve 39 and a collar 42 fixed to the casing, normally holding the stud 38 in engagement with the ratchet 37. A lever 43, pivoted at 44 to the sash, bears against the outer end of the sleeve 39 and affords means for forcing it backwardly against the resistance of the spring 41, for the purpose of disengaging the stud 38 from the ratchet after the sash has been placed in the casing and the pinion 30 is in engagement with the rack 22. Preferably this disengagement of the stud from the ratchet is accomplished automatically by the setting of the sash. The means shown for effecting this automatic action comprise a latch 45, pivoted to an outstanding bracket 46 secured to the sash and having a beveled face 47 for engaging the power end of the lever 43 and moving it outwardly by a cam action. A boss 48 on the latch 45 bears against a plane portion 49 of the flange 21, whereby the latch is held in its advanced position so long as the sash remains within the casing, the boss 48 sliding freely along the face of the flange when the sash is raised and lowered.

For convenience of manufacture the shaft 29 may be sectional, as shown, its inner end 50 being tubular and telescopically receiving the outer end, the two parts being pinned together, as represented at 51.

For the purpose of facilitating the insertion and removal of the outer sash, the intermediate stop may be made sectional, as described, the upper section 52 being permanently attached to the stile plate 15. The lower portion is preferably jointed, to flex transversely of the plane of the window, and is shown as comprising the sections 53, 54 and 55. The upper end of the section 53 carries the lower portion of the rack 22,

and may be interlocked with the end of the upper section 52. A screw 56, set through the middle section 54 of the jointed portion of the stop and entering the plate 15, will secure the parts in place. Upon the removal of the screw 56 the jointed lower portion of the stop may be drawn away from the sash 14, releasing the lock lever 43 and at the same time disengaging the rack from the pinion. In assembling the parts, the sash 14 having been properly placed within the casing the jointed portion of the intermediate stop is inserted, thereby actuating the lever 43 to disengage the stud 38 from the ratchet 37 and engaging the rack 22 with the pinion. The companion sash, that is, the inner sash may be inserted and removed when the inner stop 16 is not in place. The placing of this sash in position brings the latch 45, carried by it, in contact with the plain portion of the flange 20, thus releasing the lock of the balancing spring, while the removal of the sash from its position in the casing causes the automatic locking of the spring.

The balancing of the sash is accomplished most satisfactorily by duplicating the mechanism as shown, and thereby applying the lifting action at both of its upper corners.

While we have shown and described a desirable form of construction embodying the invention, the details may be variously modified within the scope of the invention.

We claim as our invention—

1. In combination, a casing, a sliding sash, a cylinder rotatably mounted on the sash, a non-rotatable rod carried by the sash and projecting into the cylinder, a coiled spring within the cylinder, its ends being secured respectively to the cylinder and to the rod, a ratchet carried by the rod, a sleeve longitudinally slidable on the cylinder and having a dog engageable with the ratchet, a pinion carried by the cylinder, and a rack fixed to the casing and meshing with the pinion.

2. In combination, a casing, a sliding sash, a cylinder rotatably mounted on the sash, a non-rotatable rod carried by the sash and projecting into the cylinder, a coiled spring within the cylinder, its ends being secured respectively to the cylinder and to the rod, a ratchet carried by the rod, a sleeve longitudinally slidable on the cylinder and having a dog engageable with the ratchet, a spring normally advancing the sleeve to engage the dog with the ratchet, a pinion carried by the cylinder, and a rack fixed to the casing and meshing with the pinion.

3. In combination, a casing, a sliding sash, a cylinder rotatably mounted on the sash, a non-rotatable rod carried by the sash and projecting into the cylinder, a coiled spring within the cylinder, its ends being secured respectively to the cylinder and to

- the rod, a ratchet carried by the rod, a sleeve longitudinally slideable on the cylinder and having a dog engageable with the ratchet, a spring normally advancing the sleeve to engage the dog with the ratchet, means for retracting the sleeve, a pinion carried by the cylinder, and a rack fixed to the casing and meshing with the pinion. 5
4. In combination, a casing, a sliding sash, a cylinder rotatably mounted on the sash, a non-rotatable rod carried by the sash and projecting into the cylinder, a coiled spring within the cylinder, its ends being secured respectively to the cylinder and to the rod, a ratchet carried by the rod, a sleeve longitudinally slideable on the cylinder and having a dog engageable with the ratchet, a spring normally advancing the sleeve to engage the dog with the ratchet, means for automatically retracting the sleeve when the sash is mounted in the casing, a pinion carried by the cylinder, and a rack fixed to the casing and meshing with the pinion. 10
5. In combination, a casing, a sliding sash, a cylinder rotatably mounted on the sash, a non-rotatable rod carried by the sash and projecting into the cylinder, a coiled spring within the cylinder, its ends being secured respectively to the cylinder and to the rod, a ratchet carried by the rod, a sleeve longitudinally slideable on the cylinder and having a dog engageable with the ratchet, a spring normally advancing the sleeve to engage the dog with the ratchet, a lever for retracting the sleeve, a cam latch for actuating the lever, a plate carried by the casing and normally holding the latch in advanced position, a pinion carried by the cylinder, and a rack fixed to the casing and meshing with the pinion. 15
6. In combination, a casing, a sliding sash, a counterbalancing spring carried by the sash, means for normally locking the spring when under tension, and means for automatically releasing the locking means when the sash is in the casing. 20
7. In combination, a casing, a sliding sash, a counterbalancing spring carried by the sash, means for normally locking the spring when under tension, a bar mounted on the casing for holding the locking means in release position in any position of the sash. 25
8. In combination, a casing, a sliding sash, a counterbalancing spring carried by the sash, a pinion connected to one end of the spring, means for automatically locking the pinion against rotation, a rack bar mounted on the casing and engaging the pinion, and means actuated by the rack bar for releasing the pinion locking means. 30
9. In combination, a casing, a sliding sash, a counterbalancing spring carried by the sash, a pinion connected to one end of the spring, means for automatically locking 35
- the pinion against rotation, a rack bar mounted on the casing and engaging the pinion and having a plain portion, a movable member for releasing the pinion-locking means, and being advanced by and slidably engaging the plain portion of the rack bar. 70
10. In combination, a casing, a sliding sash, a counterbalancing spring carried by the sash, a pinion connected to one end of the spring, means for automatically locking the pinion against rotation, a rack bar mounted on the casing and engaging the pinion and having a plain portion, a cam member carried by the sash for releasing the pinion-locking means and being advanced by and slidably engaging the plain portion of the rack bar. 75
11. In combination, a casing, a sliding sash, a counterbalancing spring carried by the sash, a pinion connected to one end of the spring, means for automatically locking the pinion against rotation, a rack bar mounted on the casing and engaging the pinion and having a plain portion, a lever for releasing the pinion-locking means, and a cam member carried by the sash for actuating the lever and being advanced by and slidably engaging the plain portion of the rack bar. 80
12. In combination, a pair of sliding sashes, a counterbalancing spring carried by each sash, a pinion attached to the end of each spring, a sectional center stop located between the sashes and having gear racks engageable with the two pinions. 85
13. In combination, a pair of sliding sashes, a counterbalancing spring carried by each sash, a pinion attached to the end of each spring, a sectional center stop located between the sashes and having gear racks engageable with the two pinions, the lower portion of the stop being composed of pivotally united sections. 90
14. In combination, a casing having spring advanced stile plates, flanges extending inwardly from the stile plates and forming sash stops, a pair of sashes engageable each with one of the stops, a center stop having gear racks on its side faces, counterbalancing springs mounted on each sash, pinions connected with the springs and engageable with the gear racks. 95
15. In combination, a casing, two outer stops and an intermediate stop forming runways for a pair of sashes, the inner stop being provided with a gear rack and being sectional, the lower section of such stop being formed of a plurality of parts jointed for flexure transverse to the plane of the window, sashes slideable in the ways, a counterbalancing spring mounted on one of the sashes, and a pinion connected with the spring and co-operating with the gear rack. 100
16. In combination, a casing, two outer 105
- 110
- 115
- 120
- 125
- 130

stops and an intermediate stop forming runways for a pair of sashes, a pair of sashes slideable in the runways, a counterbalancing spring mounted on one of the sashes, and a 5 pinion connected with the spring, the intermediate stop being provided with a gear rack coöperating with the pinion and extending upwardly from a point below the 10 position of the pinion when the sash is in its lowest position, such stop being sectional, the lower section carrying a part of the gear rack and being removable laterally.

17. In combination, a casing, two outer stops and an intermediate stop forming runways for a pair of sashes, a pair of sashes slideable in the runways, a counterbalancing spring mounted on one of the sashes, and a 15 pinion connected with the spring, the intermediate stop being provided with a gear rack coöperating with the pinion and extending upwardly from a point below the 20 position of the pinion when the sash is in its lowest position, such stop being sectional, the lower section carrying a part of the gear rack and being jointed for flexure transversely to the plane of the window.

18. In combination, a casing, two outer stops and an intermediate stop forming runways for a pair of sashes, a pair of sashes 30 slideable in the runways, a counterbalancing spring mounted on one of the sashes, locking means for holding the spring under tension, and a pinion connected with the spring, the intermediate stop being provided with a gear 35 rack coöperating with the pinion and extending upwardly from a point below the position of the pinion when the sash is in its lowered position, such stop being sectional, the lower section carrying a part of the gear rack and being removable laterally.

40. 19. In combination, a casing, two outer stops and an intermediate stop forming runways for a pair of sashes, a pair of sashes slideable in the runways, a counterbalancing

spring mounted on one of the sashes, locking 45 means for holding the spring under tension, and a pinion connected with the spring, the intermediate stop being provided with a gear rack coöperating with the pinion and extending upwardly from a point below the 50 position of the pinion when the sash is in its lowest position, such stop being sectional, the lower section carrying a part of the gear rack and being removable laterally and being adapted to automatically release the 55 spring-locking means when placed in position of service.

20. In combination, a casing, a sliding sash, a cylinder rotatably mounted on the sash, a non-rotatable rod carried by the 60 sash and projecting into the cylinder, a coiled spring within the cylinder, its ends being secured respectively to the cylinder and to the rod, a ratchet carried by the rod, a sleeve longitudinally slidable on the cylinder and having a dog normally engaged with the ratchet, a pinion carried by the cylinder, and a rack fixed to the casing and meshing with the pinion.

21. In combination, a casing having 70 spring-advanced stile plates flanged to form outer sash stops, a sectional intermediate stop secured to each stile plate, such stop being provided with a gear rack and its lower portion being jointed for flexure perpendicular to the plane of the window, a pair of 75 sashes slidably mounted each between one of the outer and the intermediate stops, a balancing spring carried by one of the sashes, and a pinion attached to the spring and engaging the gear rack.
